UNITED STATES PATENT OFFICE

2,337,734

OIL BURNER AND LIQUID FUEL INLET
THEREFOR

James L. Breece, Santa Fe, N. Mex., assignor to
Oil Devices, Santa Fe, N. Mex., a limited
partnership of Illinois

Application July 11, 1941, Serial No. 401,921

2 Claims. (Cl. 158—91)

My invention relates to improved means for delivering liquid fuel to a pot type burner.

One purpose is the provision of improved means for supplying the primary air with the fuel at the pilot stage of the burner.

Another purpose is the provision of means employable with the pilot baffle in a pot type burner where the baffle is set below the normal primary air supply to the burner for supplying all of the primary air necessary for the pilot stage through the fuel inlet duct.

Other purposes will appear from time to time in the course of the specification.

I illustrate my invention more or less diagrammatically in the accompanying drawing wherein:

Fig. 1 is a vertical axial section; and

Fig. 2 is a section on the line 2—2 of Fig. 1.

Like parts are indicated by like symbols throughout the specification and drawing.

Referring to the drawing, 1 indicates a base member or drum, which may be upwardly extended, as at 2, to form a radiating or combustion chamber. 3 are any suitable supporting means therefor. 4 is a bottom member with an axial air inlet 5. 6 is a supporting angle ring adapted to receive the upper flange 8 of a burner pot 7. The pot has a slightly upwardly concave bottom 9, and is provided with a plurality of primary air inlet apertures 10 located at various levels in the wall of the pot. Any suitable means may be employed for supplying secondary air to or adjacent the top of the pot. I illustrate for example a number of larger and more closely spaced secondary air inlet apertures 11.

12 is any suitable flame ring having a central aperture 13. 14 is a liquid fuel supply line extending to any suitable source of fuel not herein shown. 15 generally indicates a manually controllable valve.

It will be understood that I may employ any suitable means, manual or automatic, for controlling or varying the rate of supply of liquid fuel to the bottom 9 of the pot. In the form herein shown I illustrate an upwardly extending elbow 16, which communicates with a fuel inlet pipe 17, which extends through the drum or base 1 and through the side of the pot 7. In the form herein shown the pipe 17 extends clear to the center of the central axis of the pot and has a downwardly turned end portion 18. It will be understood, however, that the size, proportion and location of the end of the pipe 17 may be substantially varied. I find the present form efficient, however, as supplying the liquid fuel

and with it some primary air to the center of the bottom of the pot.

The primary air necessary for combustion at the pilot stage may be supplied, for example, by the upwardly extending air inlet member 19, which is in communication with the liquid fuel inlet pipe 17, as for example by the coupling 20. I may employ a pilot ring 21, mounted on any suitable supports, such as pins 22, and located below the lowest row of primary air inlets 10 in the side wall of the pot 7. It will be understood that I supply through the passage 18 sufficient air to support combustion at the pilot stage.

The burning rate is controlled by controlling the supply of liquid fuel, and when the valve 15 or equivalent means is set to supply a minimum or pilot volume of fuel, all the air necessary for combustion below the pilot ring 21 enters through the inlet 19 and along the pipe 17 with the fuel. At such stage the pilot ring 21 serves to prevent down drafts from the upper portion of the pot, which would disturb the balance of combustion in the area below the pilot ring, and a low flame is maintained with a minimum deposit of free carbon.

It will be realized that, whereas I have described and illustrated a practical and operative device, nevertheless many changes may be made in the size, shape, number and disposition of parts without departing from the spirit of my invention. I therefore wish my description and drawing to be taken as in a broad sense illustrative or diagrammatic, rather than as limiting me to my precise showing.

For example, the inlet passage 18 may be located, if desired, within the space between the base 1 and the pot 7. The use and operation of my invention are as follows:

In pot type burners a low turndown is desirable. This low turndown may be obtained by providing, in effect, a duplex burner with a pilot baffle in a lower part of the pot. I employ the baffle 21, which is located below the lowest of the apertures 10 in the pot wall. The apertures 10 serve as primary air inlet apertures for the full combustion stage, the secondary air being supplied by the upper apertures 11, the combustion at the high stage taking place at or above the ring 12.

It will be understood that in a so-called hydroxylating burner the primary air combines with the hydrocarbon vaporized by the heat of combustion to form a mixture, which in turn is finally burned after it receives a supply of secondary air. When the burner is operated at low or pilot stage,

combustion may take place at or above the pilot ring 21. For the pilot stage I prefer to supply the primary air along the duct 17, which also serves as an oil delivery duct. The passage duct is of sufficient cross sectional area to admit sufficient primary air to support combustion at or about the level of the ring 21.

At the pilot stage sufficient fuel may be supplied by the control means diagrammatically shown at 18 to maintain pilot combustion at the level of the ring 21. The inlet 19 and the pipe 17 are of sufficient gauge or cross sectional area to admit all the primary air necessary for the hydroxylation of the mixture. The fuel flowing in along the inlet or nozzle 17, in the presence of the air admitted through the pipe 19, is subjected to the heat of combustion at the level of the pilot ring 21, and complete hydroxylation takes place. The hydroxylated mixture then receives its secondary air through the apertures 10 and is burned at or above the level of the ring 21.

It may also happen that an even lower turndown is desired, and in such event, with the structure as shown, it will be understood that combustion may take place at or near the outlet of the downturned passage portion 18. This low turndown, of course, is merely obtained by limiting the flow of fuel to a very low rate, and the small amount of fuel so delivered is mixed with the air and completely hydroxylated by the combustion taking place at or near the downwardly turned end 18 of the inlet 17.

I claim:

1. In combination, in a pot type burner, a burner pot having a circumferential wall with a plurality of primary air inlet apertures therein,

means for supplying secondary air at a level adjacent the top of the pot, a central apertured baffle ring located between the top and bottom of the pot, and below the lowest of the primary air inlet apertures in the pot wall, a liquid fuel inlet member extending into the pot and into the space below said baffle ring, said inlet member having a delivery aperture located in general alignment with the axis of the pot and with the aperture of said baffle and at a level closely adjacent the bottom of the pot, means for delivering liquid fuel to said fuel inlet member and means for admitting air to the interior of said liquid fuel inlet member for mixture with the fuel flowing therealong.

2. In combination, in a pot type burner, a burner pot having a circumferential wall with a plurality of primary air inlet apertures therein, means for supplying secondary air at a level adjacent the top of the pot, a central apertured baffle ring located between the top and bottom of the pot, and below the lowest of the primary air inlet apertures in the pot wall, a liquid fuel inlet member extending into the pot and into the space below said baffle ring, said inlet member having a delivery aperture located in general alignment with the axis of the pot and with the aperture of said baffle and at a level closely adjacent the bottom of the pot, means for delivering liquid fuel to said fuel inlet member and means for admitting air to the interior of said liquid fuel inlet member for mixture with the fuel flowing therealong, the liquid fuel inlet member having its end downwardly turned and terminating closely adjacent the bottom of the pot.
